BANDING MACHINE

Coley Walten Gunter and James Walter Howe,
Jr., Durham, N. C., assignors to Wright Ma-
chinery Company, Durham, N. C., a corporation
of North Carolina

Application December 27, 1951, Serial No. 263,624

5 Claims. (Cl. 226—80)

1

This invention relates to banding machines and particularly to machines for applying shrinkable tubular bands about the neck and cap of a bottled product. It is well known to apply such bands to bottles and the band, upon shrinking, forms a seal between the cap and bottle neck to protect the contents of the container. Commonly such bands consist of a tubular length of regenerated cellulose. Such material when wet expands to a considerably larger diameter rendering it easy to slip the same over the neck and cap of a bottle. Upon drying the material shrinks and draws tightly about the lower portion of the cap and the bottle neck, constituting an effective seal.

In general the machine of the present invention includes novel means for opening a short tubular length of the shrinkable material and to hold the same stationary, in opened condition, directly over the path of travel of a capped bottle. The mechanism for moving the bottle comprising novel elements mounted on a moveable carrier whereby the carrier may move continuously but the bottle carried thereon is caused to move upwardly to project its cap and neck into the opened tubular element without appreciable movement in the direction of carrier travel during the projecting cycle. Novel means are also provided for holding the bottle in a predetermined position relative to the mechanisms carried by the turret and for releasing bottles therefrom at a discharge station.

It is therefore an object of this invention to provide a machine capable of unusually rapid handling of the bottles and applying bands thereto.

It is a further object of this invention to provide a high speed banding machine that is relatively simple in construction and economical to produce.

Another object of this invention is to provide a high speed banding machine wherein a bottle is carried by a continuously moveable carrier but wherein the forward motion of the bottle itself is periodically stopped while the band is applied.

Another object of this invention is to provide a banding machine arranged to hold an opened band stationary and to move the bottle thereinto, thus eliminating the necessity for complicated band handling apparatus.

A still further object of this invention is to provide a banding machine having improved means for opening a short length of tubular band material.

Another object of this invention is to provide

2

a machine of the type described wherein the motion of a continuously moving carrier is employed to project a bottle carried thereby laterally of the direction of motion without moving it in that direction.

A still further object of this invention is to provide, in a machine of the type described, clamping means for the bottle bearing a novel relationship to the clamp operating mechanisms.

Still further objects and advantages will become apparent to those skilled in the art as the description proceeds in connection with the accompanying drawings wherein:

Fig. 1 is a side elevational view of a machine constructed in accordance with the present invention, the base portion thereof and a portion of a side wall being broken away;

Fig. 2 is a top plan view of that portion of the machine shown in Fig. 1;

Fig. 3 is an enlarged sectional view of a portion of the machine shown in Figs. 1 and 2 taken substantially along the line 3—3 of Fig. 1;

Fig. 4 is a sectional view taken substantially along the line 4—4 of Fig. 3;

Fig. 5 is a fragmentary sectional view taken substantially along the line 5—5 of Fig. 3;

Fig. 6 is a fragmentary sectional view taken substantially along the line 6—6 of Fig. 3; and

Fig. 7 is a view similar to Fig. 6 but showing the parts in different relationship.

Referring first to Figs. 1 and 2, the machine comprises generally a base structure 2 having thereon a rotatable turret 4 driven in rotation about a vertical axis by a main shaft 6 from a suitable source of power housed within the base 2 but not shown in the drawings. The articles to be handled may comprise bottles A having screw or other caps thereon. Such articles may be fed into the device by an infeed conveyor 8. A star wheel 10, driven in timed relation to the turret 4 operates to space and feed bottles in sequence along a guide rail 11 to successive platforms 12 and clamping means 162 mounted in spaced relation on the turret 4. Bottles thus fed to the turret are carried thereby past a fixed station, designated generally by letter B in Fig. 2 where mechanism to be described later causes the platforms 12 and clamps 162 to rise vertically without forward movement to project the bottles into an opened band. The platform is then released

for downward movement and the band thereon is released by the holding means to thereafter move with the bottle until the latter arrives at a discharge station C where the clamping means 55 are released and a guide rail 16 and discharge

sweeping wheel 18 remove successive bottles from the turret and deliver them to a take-away conveyor 20.

The tubular material is supplied to the machine in the form of a continuous and elongated flattened tube 24 wound on a reel or the like and kept in a tank (not shown) of suitable liquid material such as a formaldehyde and glycerine solution or formaldehyde and water. The purpose in keeping the tubular material immersed in the liquid is to keep it in an expanded condition to facilitate its application to a bottle neck. The material of the tube and the manner of keeping it soaked to expanded condition is a well known feature of the prior art and need not be discussed in greater detail. The tubular material on the reel is led from the tank and trained over suitable guide means to extend to guide roller 22 (see Figs. 1 and 2) near the top of the machine. From there the continuous tube 24 is trained downwardly into a feeding and cutting mechanism designated generally at 26 in Fig. 1. The feeding and cutting mechanism per se forms no part of the present invention and is described in detail and claimed in co-pending application Serial No. 99,464, filed on June 6, 1949 by Andrew O. Russell, Michael G. Jones and William W. Watts. In general, the cutter mechanism is operated in timed relation to the rotation of the turret 4 by means of a main cutter shaft 28, driven from the same source of power as that employed to rotate the turret 4 and the wheels 10 and 18. The shaft 28 actuates mechanism for feeding predetermined lengths of tubular material to a cutting knife shown schematically at 30 in Fig. 6. The knife is operated in timed relation to the rest of the mechanism to sever the end of the tube 24 into predetermined lengths. The mechanism up to this point is fully covered and described in the co-pending application referred to.

A novel feature of the present invention includes the means for gripping and spreading the severed end portion 32 (Fig. 6) of the tubular material 24. This mechanism is driven by the shaft 28. A pair of brackets 34 (Fig. 1) attached to the sides of the cutter mechanism 26 extend therebelow and across the bottom of that cutter mechanism on opposite sides of the shaft 28. Referring now particularly to Figs. 3, 4 and 5, the brackets 34 support a guide frame comprising a lower fixed plate 36, an intermediate fixed plate 38 and a fixed top plate 40. Longitudinally extending spacer strips 42 (Fig. 5) are interposed between the edges of the plates 36, 38 and 40 thus defining elongated guideways between the plates and spacers. Suitable fastening means such as rivets 44 may be employed to hold the guide members in fixed assembled relationship. The space between plates 38 and 40 serves to guide an upper slidable plate 46 for longitudinal movement in the frame and the space between plates 36 and 38 serves as a guide for a second or lower slidable plate 48. A fixed pin 50 extends vertically through the guide plates adjacent one end of the guide structure and constitutes a pivot for a transverse lever 52 operating in a cut-away portion 54 of the intermediate guide plate 38. One end of the transverse lever 52 is provided on its underside with a roller 56 extending downwardly into a transverse slot 58 in the lower slidable plate 48. The other end of lever 52 is provided on its upper side with a roller 60 extending into a transverse slot 62 in the upper slidable plate 46. Each of the slidable plates 46 and 48 are

provided with longitudinally extending slots 64 and 66 through which stationary pin 58 extends, thus permitting the plates to slide longitudinally of the frame structure without interference from pin 50. It will be apparent from a study of Figs. 3, 4 and 5 that the transverse lever 52 will enforce the top plate 46 to move to the left as seen in Fig. 4 when the bottom plate 48 is caused to move to the right. In other words the lever 52 and related elements forces the plates 46 and 48 to reciprocate in opposite directions. The lower sliding plate 48 is provided with a cam following roller 68 projecting downwardly therefrom and through an elongated slot 70 in the lowermost guide plate 36. A grooved cam 72 is fixed to the shaft 28, such as by set screws 74 or the like, and is provided with a cam groove 76 in its uppermost face. As clearly seen in Fig. 3, the cam groove 76 is a simple circular groove concentric to shaft 28 throughout the major portion of its periphery but is provided with a portion 78 nearer to the shaft 28 than the remainder of the groove. As will be obvious, rotation of the cam 72 will hold the lowermost slideable plate 48 in its left-hand position as seen in Fig. 4 for most of each revolution of the cam but will move that plate to the right, then back again to the left, for a purpose to be described, once during each revolution. It is to be remembered that all reciprocatory movements of the plate 48 produce an equal and opposite reciprocation of the upper slideable plate 46. The frame plates 36, 38 and 40 are provided with aligned openings through which shaft 28 passes to extend into and drive the cutter mechanism. The slideable plates 46 and 48 are provided with longitudinally extending slots 80 and 82 respectively, through which the shaft 28 also passes. The elongated slots 80 and 82 permit reciprocatory movement of the plates 46 and 48 without interference from shaft 28.

The uppermost sliding plate 46 extends a substantial distance to the right beyond the end of the guide structure therefor and is cut away as at 84 (Fig. 3) to provide a notch extending inwardly from one edge of the plate, said notch being of substantial longitudinal dimension, materially greater than the extent of reciprocation of the plates. The notch 84 is cut into an edge of plate 46 adjacent but spaced from the extreme end of the plate, thus providing a transverse bar or support 86 at the outermost end of the plate 46. The support portion 86 has a suction head 88 mounted thereon. The suction head 88 may be of any usual or conventional design and is carried with the portion 86 of plate 46 in its reciprocatory movements. A suitable flexible tube or conduit 90 (see Figs. 1, 2 and 4) connects the suction head 88 to a source of vacuum, to be described later. A second suction head 92 is mounted on the right-hand extremity of the lowermost sliding plate 48 and extends upwardly therefrom, at all times within the notch 84, to a position opposite the suction head 88. The suction head 92 is connected to the source of vacuum by means of a flexible conduit or tube 94.

It will be seen that as the plates 46 and 48 are periodically reciprocated, the suction heads 88 and 92 are brought together momentarily, then separated to and held in the relative positions shown in Fig. 4. The mechanism is so timed that the suction heads 88 and 92 are brought together as the knife 30 severs the end portion 32 of tubular material 24 and at that time a

control valve is operated in timed relation to the cutter mechanism to evacuate the suction heads thus firmly gripping opposite sides of the tubular material 32. The suction heads are maintained in communication with the source of vacuum while the plates 46 and 48 are reciprocated to move the suction heads apart and the suction heads thus effect opening of the tubular material by pulling opposed walls apart to an extent sufficient to receive the bottle cap and neck portion of a bottle. The sliding plate and suction head mechanism is so positioned relative to the turret 4 that the opened tube 32 is held stationary directly above the path of travel of the bottles A. The conduits or tubes 90 and 94 are preferably of a flexible nature whereby the ends connected to the suction head may readily move therewith while the other ends thereof may be connected to a suitable fixture 96 (Fig. 1) whereby both tubes are in communication with the passages of a valve 98. Suitable operating mechanism 100 for the valve 98 is actuated by a movable part of the cutter mechanism (not shown) to admit and cut off vacuum from the suction heads in timed relation to movement of the sliding plates 46 and 48. A conduit 102 may connect the valve 98 to a suitable vacuum pump (not shown) in the base of the machine. A second conduit 104 may supply vacuum to other portions of the cutter mechanism, with which the present application is not concerned.

As shown in Fig. 3 the turret 4 rotates in a clockwise direction, as indicated by the arrow, and it is to be noted that the notch 84 in plate 46 is opened to the side thereof in which the capped bottles move after passing the banding station. After a bottle has been lifted and projected into the expanded band 32 the valve 98 is operated to cut off the vacuum from the suction heads 92 and 98 and to thus release the band 32 for movement with bottle A. The bottle is simultaneously released for movement with the turret 4 in the direction of movement of the turret and for lowering movement relative thereto, all as to be described in detail later. After the band 32 is released by suction heads 92 and 98 the bottle and band immediately start moving with the turret 4 through the open side of the notch 84, permitting the bottle and band to move laterally away from the suction heads without interference from any portion of the sliding plates 46 or 48.

Reference will now be made to Figs. 3, 4, 6, and 7. The turret 4 is provided with a plurality of circumferentially spaced openings 110 arranged to receive the lowermost portions of the platforms 12 on which bottles A are carried. The platforms 12 may comprise an upper plate member and a lower or supporting plate 112 adapted to extend into the openings 110 while the upper plates 12 overlie the edges of the opening to thereby limit the downward movement of the platforms relative to the turret. Each of the plates 112 has welded or otherwise affixed thereto a downwardly and forwardly extending U-shaped guide plate 114. The guide plates 114 are, as stated, of generally U-shape with the base of the U portion being affixed to the plate 112 and the spaced legs thereof extending downwardly and forwardly in the direction of movement of the turret 4. The turret 4 is provided with brackets 116 fixed to the undersurface thereof adjacent the leading edges of openings 110 and each of the brackets 116 is provided with rearwardly and vertically extending spaced guide plates 118 (see

particularly Fig. 4). Each of the plates 118 is provided on its inner face with a guide groove 120 extending parallel to the direction of extent of the U-shaped plate 114 and directly opposite the edges of plates 114. The outer edges of the legs of each plate 114 are provided with a series of aligned rollers 122 extending into the guide grooves or trackways 120. It is apparent that the rollers 122 function to support the plates 114 and platforms 12 on turret 4 for sliding movement upwardly and rearwardly of the direction of motion of the turret. Each of the plates 118 may be provided with a suitable stud 124 having one end of a tension spring 126 connected thereto and to the ends of the legs of plates 114 whereby to urge the platforms 12 to their lowermost and forward positions. Clearly the platforms may be raised by movement of rollers 122 in grooves 120 against the action of springs 126. Since all of the platform lifting means are identical only one will be described in detail. A transverse pivot pin 128 extends between the legs of the U-shaped plate 114 adjacent the upper ends of those legs. Links 130, of which there are two, are each pivoted at one end about the pin 128 between the downwardly and forwardly extending legs of the U-shaped plate 114. The links 130 carry a transverse pivot pin 132 at their lowermost ends. A cam following roller 134 is rotatably mounted on the pin 132 between the lower ends of links 130. Links 136, of which there are two, are pivoted at one end to a bracket 138 fixed to the underside of turret 4 forwardly of the brackets 116 and are pivoted at their lowermost ends about the pin 132 outwardly of the links 130. It will be clear that upward movement of the platform 12 will cause links 130 to move upwardly therewith and, through pin 132, will cause the links 136 to swing upwardly about their pivotal connection to brackets 138.

A portion of the base frame of the machine, as indicated at 140, has fixedly mounted thereon a cam element 142. Preferably the cam element 142 is arcuate in plan view so that its upwardly extending edge lies directly in the path of movement of the rollers 134. The cam element 142 is provided with a riser edge 144 extending upwardly and slightly forwardly with respect to the direction of movement of the turret, to a crest 146 then downwardly at a relatively gradual inclination to define a cam edge 148. The cam element 142 is so positioned on the frame that the roller 134 first contacts the riser portion 144 of the cam at the time a bottle A arrives at a position substantially directly below an opened tubular section 32 of the shrinkable material. The operation of the mechanism is so timed that successive tubular sections 32 are opened and held in opened position at the time each successive bottle arrives at a position directly thereto. The conditions existing at this time are illustrated in Fig. 6. It is to be remembered that with the parts in the relationship shown in Fig. 6 the turret 4, guide plates 118, links 136 and 130 and roller 134 are moving toward the left at a uniform rate of speed. As the roller 134 contacts the riser surface 144 of cam 142 the forward motion of the roller is stopped and it tends to move to the right and upwardly relative to the turret 4. The upward swinging movement of link 136 and roller 134, by pushing on link 130, causes the U-shaped plate 114 and platform 12 to slide upwardly and rearwardly relative to the turret 4 to the position shown in Fig. 7. It will be seen that the opening 110 in Fig. 7 is in a

position to the left, relative to the cam 142, of its position shown in Fig. 6. The angle of inclination of the guide grooves 120 and the angle of inclination of the riser surface 144 of cam 142 are so selected and related to the lengths of links 130 and 136 that movement of the platforms 12 in an upwardly and rearwardly direction relative to the turret 4 is such that the bottles A rise substantially exactly vertically relative to any fixed portion of the frame, from the position of Fig. 6 to the position of Fig. 7. By properly positioning the cam 142 relative to the position of the suction heads 88 and 92 the bottle is caused to move upwardly along a vertical axis extending centrally through the open tube 32 and to such an extent that the bottle cap and a portion of the bottle neck are moved upwardly into the tube of shrinkable material, as shown in Fig. 7.

As the turret 4 continues to move to the left from a position shown in Fig. 7 the roller 134 passes over the crest 146 of the cam and starts down the gradual incline 148 under the influence of gravity and springs 126. It will be apparent that downward movement of the roller 134 permits the platform and plate 114 to start moving downwardly along the guideways 120 and thus move forwardly in the direction of the turret at a greater rate of horizontal speed and to also move downwardly relative to turret 4. At the time the roller 134 reaches the crest 146 of cam 142 the cutter mechanism operates valve 98 to release the vacuum from suction heads 88 and 92 and thus drop the tube 32 onto the bottle. The bottle may then move to the left as shown in Fig. 7 and carry the tube 32 therewith outwardly of the open side of the notch 84 in plate 46. As soon as the roller 134 moves beyond the influence of cam 142 the platforms 12 are in their lowermost position as shown in Fig. 6 and they remain in that position until they again come around to the banding station just described and the described cycle is then repeated.

Referring now to Figs. 2, 3 and 4, each platform 12 is shown as provided with a pair of upstanding pivot pins 160. Each pivot pin 160 pivotally supports a bottle holding clamp jaw 162. A tension spring 164 is connected to each of the jaws 162 and urges those jaws into bottle clamping position. Furthermore, each of the jaws 162 is provided with a toothed portion 166 (see Figs. 3 and 4) whereby the jaws are caused to move in equal amounts about their respective pivot pins and to always come together to clamp and hold a bottle in a predetermined central position on the platform 12. One of the clamping jaws on each platform is provided with an inward extension 168 having a cam following roller 170 on its upper surface. A fixed cam 172 (see Fig. 2) is supported in fixed position relative to the frame to extend substantially from the discharge station C to the loading station defined by the star wheel 10. The cam 172 may be fixedly supported relative to the frame in any suitable manner and is provided with a cam edge portion 174 extending into the path of movement of the rollers 170. It will be apparent from Fig. 2 that as each banded bottle and its platform 12 arrive at the discharge station, the roller 170 will engage cam edge 174 to swing the clamping jaws 162 to open position and thus release the bottle on that platform to the action of the discharge sweep 18. The clamping jaws are held, by cam edge 174, in open position until the successive platforms arrive at the loading station and a bottle A deposited thereon. At that time the

15
20
25
30
35

rollers 170 pass off the cam edge 174 and springs 164 cause the jaws to center the bottle on the platform and hold it firmly in that position. Shortly thereafter the bottle and its platform arrive at the banding station at which an open band 32 is being held and the mechanism of Figs. 6 and 7 operates to lift the bottle and platform along with the clamping means upwardly to project the bottle and neck into the opened band in the manner described. By the described arrangement applicant employs clamping jaws engageable with a stationary cam and wherein the clamping jaws are carried by a vertically moveable supporting structure. By employing a short fixed cam 172 the cam is positioned in the path of movement of the rollers 170 during those portions of the cycle when it is desired to operate the clamping jaws but the rollers 170 are free to then move vertically at the banding station without interference from any part of the cam or other structures.

As shown in Figs. 4, 6, and 7 each of the clamping jaws 162 is provided with a recess 180 at the edge adjacent the companion clamping jaws. The recesses 180 complement each other, when the jaws are in closed position, to form an opening slightly greater than the diameter of the bottles being handled. A block or blocks 182 of suitable resilient material is fixed to the upper surface of each clamping jaw 162 and the resilient blocks 182 are provided with complementary openings in their adjacent edges of such size as to snugly embrace the sides of the bottles A when the jaws are in closed position. The resilient blocks thus hold the blocks properly positioned on the platform without danger of breaking the bottles when springs 164 move the clamping jaws to closed position.

The machine described herein is obviously capable of unusually high speeds of operation since it is not necessary to start and stop massive components. All of the heavy portions of the machine move at a uniform and constant rate without the production of high acceleration forces. The only parts movable intermittently in such manner as to produce acceleration forces are the relatively small platforms and the structures fixed thereto. The acceleration of those elements is in a direction transverse to the direction of movement of the turret and the cam 142 and links 130 and 136 may be so designed as to minimize shocks due to acceleration.

If desired, a suitable counting mechanism 180 (see Fig. 2) may be attached to the machine of the present invention to indicate the number of bottles processed.

While a single specific embodiment of the invention has been shown and described herein it will be obvious to those skilled in the art that many departures from the described details may be made within the spirit of the invention. The described embodiment is intended as illustrative only, the invention embodying all other modifications falling fairly within the scope of the appended claims.

We claim:

1. In a machine for applying tubular bands to an article; band spreading and holding means comprising, a pair of elongated superposed plates, means guiding said plates for longitudinal reciprocation along parallel paths, one of said plates having a notch in one longitudinal edge thereof adjacent to but spaced from one end thereof, a suction head on said one end adjacent said notch, a second suction head on

the end of the other plate adjacent said notch, the path of reciprocation of said second suction head being at all times within the confines of said notch whereby said notch provides an unobstructed passageway for the article from between said suction heads toward and extending outwardly of an edge of said plates.

2. A device as described in claim 1 wherein the ends of said plates supporting said suction heads project longitudinally beyond said guiding means.

3. A device as described in claim 1 including means for simultaneously reciprocating said plates and suction heads in opposite directions.

4. A device as described in claim 1 including a lever pivoted intermediate its ends on a fixed axis, each end of said lever being connected to one of said plates, and means for reciprocating one of said plates.

5. A device as described in claim 1 including a lever between said plates and pivoted at its mid point on a fixed axis, one end of said lever having a pin-and-slot connection with one of

said plates and the other end thereof having a pin-and-slot connection with the other of said plates, a longitudinal slot through each of said plates in such position that portions thereof are at all times superimposed, a shaft extending through said slots, a cam on said shaft adjacent one of said plates, and cam follower means on said one of said plates, engageable with said cam whereby said one plate is reciprocated by said cam upon rotation of said shaft.

COLEY WALTON GUNTER.
